[57] CLAIM

The ornamental design for a camping light standard, as shown and described.

DESCRIPTION

FIG. 1 is a perspective view of a camping light standard showing my new design, a camp light being shown in broken lines for illustrative purposes only;

FIG. 2 is a front elevational view thereof;

FIG. 3 is a rear elevational view thereof;

FIG. 4 is a right side elevational view thereof with the left side elevational view being identical thereto;

FIG. 5 is a bottom plan view thereof;

FIG. 6 is a top plan view thereof;

FIG. 7 is a perspective view of a second embodiment of my new design on an enlarged scale;

FIG. 8 is a front elevational view thereof;

FIG. 9 is a right side elevational view thereof;

FIG. 10 is a left side elevational view thereof;

FIG. 11 is a rear elevational view thereof;

FIG. 12 is a top plan view thereof;

FIG. 13 is a bottom plan view thereof;

The standard is broken away in FIGS. 1, 2, 3, 4 and 7 for convenience of illustration.
